DOWEL PINNING MACHINE

Kervin D. Revell, Wauchula, Fla.

Application April 9, 1951, Serial No. 220,077

9 Claims. (Cl. 144—31)

1

This invention relates to new and useful improvements in a machine for fabricating structure to be used in the manufacture of crates, and more particularly pertains to mechanism for automatically and continuously securing blocks of wood, or the like, together by means of dowel pins and a suitable adhesive agent.

The primary object of this invention is to drill holes in blocks, position the blocks in spaced relation to each other with the holes therein in alignment, position the dowel pin between the spaced blocks in alignment with the holes therein, and to then press the blocks together to properly seat the dowel pin in the holes.

Another important object of the present invention is to provide a machine of this character in which means is provided for yielding during urging of the blocks together in the event the dowel pin is not properly aligned with the dowel pin receiving openings in the blocks, so that operation of the machine will not be halted by such a stoppage or portions of the machine broken.

Still another important object of the present invention, closely allied to the preceding objects, is to clean and condition the adjacent surfaces of the blocks to be complementary to each other before the blocks are pushed together, so that a tight joint will be formed between the blocks.

Yet another important object of this invention is to apply a suitable binding or adhesive agent to the dowel pin before the blocks are pushed together.

Further objects of this invention are to trim the sides of the panel formed by pinning of the blocks together and to cut an opening in one side of the panels to serve as a hand-hold opening when the completed panel is assembled in a crate.

Other important objects of this invention are to provide a machine of this character which may be manufactured at a relatively low cost, which will be reliable and durable in operation, and which will require very little supervision and only necessitate the supply of raw materials thereto.

A meritorious feature of the present invention resides in the means provided for feeding blocks to the drilling machine, and the structure affording the coordination between the removal of the blocks from the feeding hoppers and the movements of the drilling machine, whereby a drilled block is removed from a feeding hopper and a new block placed in position to be drilled while a block in the other feeding hopper is being drilled.

Another important feature of the present invention resides in the conveying means and the aligning means, and the structure affording co-

2

ordination between the operation of such means so as to move each pair of blocks into the pusher or pinning station with the blocks properly spaced and the holes therein in alignment for the proper positioning of the dowel pins therebetween.

Still another important feature of the present invention resides in the structure at the pinning station for holding the blocks against longitudinal movement and for yieldingly urging the blocks together in synchronization with the delivery of drilled blocks to the pinning station.

Yet another notable feature of the present invention resides in the structure for delivering dowel pins with glue applied thereto to a position adjacent the pinning station, together with the structure synchronized in movement with block pushing structure for moving dowel pins to and holding the same in proper relation to the blocks until the opposite ends of such pins are beginning to enter the holes in the blocks.

Final important features to be specifically enumerated herein reside in the means for trimming the opposite ends of the pinned blocks, together with the transversely reciprocating carriage for moving the pinned blocks into the rotary cutter, and the means affording the synchronization between the delivery of pinned blocks to this carriage and the reciprocation of the carriage.

These, together with various ancillary objects and features of the invention which will become apparent as the following description proceeds, are attained by the present invention, a preferred embodiment of which has been illustrated by way of example only in the accompanying drawings, 35 wherein:

Figures 1 and 2 are each fragmentary plan views of the machine drawn to the same scale and, taken together, constitute a top plan view of the entire machine, with certain details being shown in dotted lines in these views;

Figure 3 is an enlarged transverse vertical sectional view taken upon the plane of the section line 3—3 of Figure 1;

Figure 4 is an enlarged transverse vertical sectional view taken upon the plane of the section line 4—4 of Figure 1, and in which an alternative position of the aligning mechanism is shown in dotted outline;

Figure 5 is another enlarged transverse vertical sectional view taken upon the plane of the section line 5—5 of Figure 2, hidden details being indicated in dotted outline and the aligning mechanism being shown in the alternative position in dotted outline;

Figure 6 is an enlarged broken transverse sec-

tional view taken upon the broken section line 6—6 of Figure 2, showing the machine in a subsequent stage of operation than that shown in Figure 2;

Figure 7 is an enlarged broken longitudinal sectional view of the machine, this view being taken upon the plane of the section line 7—7 of Figure 2:

Figure 8 is another enlarged longitudinal sectional view, this view being taken upon the plane of section line 8—8 of Figure 2;

Figure 9 is an enlarged fragmentary detail view, partially in section, illustrating the construction of a portion of the aligning mechanism;

Figure 10 is an enlarged fragmentary top plan view of the hand-hold cutting mechanism shown in Figures 2 and 6, certain hidden details being shown in dashed outline;

Figure 11 is an enlarged fragmentary detail view of the chain construction for moving the blocks;

Figure 12 is an enlarged top plan detail view of a portion of the dowel pin 50 mechanism, this view being taken upon the plane of the line 12—12 of Figure 5, and in which an alternative position assumed by the same is shown in dotted lines;

Figure 13 is a top plan view of the machine with portions thereof removed to illustrate particularly the power trains and the manner in which the operation of the various assemblies is synchronized for continuous operation;

Figure 14 is a perspective view of the finished product, with the dowel pins therein indicated in dotted lines;

Figure 15 is a fragmentary vertical sectional view, this view being taken upon the plane of the broken section line 15—15 in Figure 1;

Figure 16 is also a fragmentary vertical sectional detail view, this view being taken upon the plane of the broken section line 16—16 in Figure 1;

Figure 17 is a vertical sectional detail view taken upon the plane of the section line 17—17 in Figure 2; and

Figure 18 is a vertical sectional detail view, this view being taken upon the plane of the section line 18—18 in Figure 1.

Reference is now made more specifically to the accompanying drawings, wherein like numerals designate similar parts throughout the various views, and in which the reference numeral 10 designates the dowel pinning machine generally.

In general, and as best shown in Figures 1 and 2, the machine 10 comprises an elongated frame 12 of any suitable construction and which is preferably of welded steel construction. Adjacent one end of the frame 12 is mounted a drilling machine or assembly 14 which reciprocates to alternately drill openings in the adjacent sides of blocks 16 supplied to the machine 10 in the feed hoppers or chutes 18 and 20.

Conveyor chains 22 and 24 are adapted to alternately move the blocks 16 from the hoppers 18 and 20 as they are drilled along the top 26 of the frame 12 along parallel paths in the direction indicated by the arrow 28.

During the movement of the blocks 16 from the drilling assembly 14, the adjacent sides of the blocks 16 are planed by the joiners 30 and 32, which will be explained more fully herein-after.

Inasmuch as the chains 22 and 24 travel at the same velocity, the blocks 16 proceed in staggered relation past the joiners 30 and 32, and it is therefore necessary, before the blocks 16

can be pinned together, to place the blocks 16 in side-by-side relation. For this purpose, an alignment mechanism, designated generally at 34, is provided, which receives the blocks 16 moved by the chain 24 from the hopper 20, and moves the same toward the chain 22 in the direction indicated by the arrow 36 to position such blocks on the conveyor chain 38. The conveyor chain 38, like chain 22, travels in the direction indicated by the arrow 40, and at the same velocity. As will be more fully described subsequently, the character and timing of the chains 22, 24, 38 and the aligning mechanism 34 are such that the blocks 16 will travel in side-by-side relation on the chains 22 and 38, as indicated in phantom lines 42 and 44, respectively. To facilitate an understanding of the operation of the aligning mechanism 34, the simultaneous position of a pair of blocks is indicated in full lines 46 and 48, before the latter is acted upon by the aligning mechanism 34.

The chains 22 and 38 move the blocks to a pinning station, designated generally at 50. It is at the pinning station that the pair of blocks moving thereto are first properly positioned in spaced relation with the bores therein in alignment, after which dowel pins with glue applied thereto are placed between the blocks to be received in the openings in the blocks, and finally the blocks are pushed together to complete the pinning operation. The structure for performing the above operation at the pinning station 50 will be described and the operation thereof explained in detail presently.

A pair of conveyor chains 52 are arranged to move the panel formed by pinning of the blocks together at the pinning station 50 to the right as viewed in Figure 2 and as shown by the arrow 54.

The chains 52 move the panel to a position to be moved by conveyor chains 56 in the direction indicated by the arrow 58, that is, at right angles to the travel path of the chains 52. The panels are moved by the conveyor chains 56 between a pair of rotary saws 60 to trim the edges of the panels perpendicular to the juncture of the blocks forming the same, the panels being held down during the period of their engagement with the saws 60 by suitable hold-down means 62.

After passing the saws 60, the chains 56 move the panels to a hand-hold cutting assembly, designated generally at 64. As will be presently explained in detail, the assembly 64 serves to shift the panels laterally from the travel path of the chains 56 to engage the rotary cutter 66 to cut a hand-hold therein to form the completed product 68 illustrated in Figure 14.

The completed product 68 is a rectangular shaped panel formed of blocks 16 joined by dowel pins 70 and having a hand-hold 72 cut therein. It will be understood that the product 68 is particularly adapted to form the end walls of a crate construction, not shown, of which the same is to form a part.

Obviously, the proper operation of the machine 10 requires a high degree of synchronization between the operation of its component parts, and since the necessary synchronization is attained by the drive means employed in the machine, this portion of the machine will be explained now in order to make the manner in which the synchronization is achieved apparent as the various components are explained in detail.

Accordingly, attention is now directed to Figure 13, wherein it will be seen that the prime mover 74 drives a countershaft 76 through a belt 78 entrained over sprockets 80 and 82 fixed on the output shaft of the prime mover 74 and the shaft 76, respectively. The main shaft 84 is driven from the countershaft 76 by means of a chain 86 entrained over sprockets 88 and 90 fixed on the shafts 76 and 84, respectively.

For a reason to become apparent presently, eccentrics 92, 94, 96 and 98 are fixed on the main shaft 84.

A shaft 100, extending transversely to the longitudinal dimension of the frame 12, is driven from the main shaft 84 by meshing bevel gears 102 and 104 fixed on the shafts 84 and 100, respectively. Further shafts 106, 108 and 110 are also journaled on the frame 12 transverse to the longitudinal dimension thereof and the chains 52 are entrained over sprockets 112 and 114 fixed to the shafts 100 and 106, respectively. The chain 22 is entrained over sprockets 116 and 118 fixed on the shafts 106 and 110, respectively, and the chain 38 is entrained over sprockets 120 and 122 fixed on the shafts 106 and 108, respectively. In a similar manner, the chain 24 is entrained over sprockets 124 and 126 fixed on the shafts 108 and 110, respectively. However, for a reason to become apparent subsequently, the lower flight of the chain 24 is entrained under an idler sprocket 128 on a shaft 130 (see Figure 3).

With continued reference to Figure 13, a short, longitudinally extending shaft 132 is rotatably mounted on the frame 12 on the side thereof opposite the main shaft 84, and the chains 56 are entrained over sprockets 134 and 136 fixed to the shafts 84 and 132, respectively.

In addition, shafts 138, 140 and 142 are also journaled on the frame 12 for rotation transverse to the longitudinal dimension thereof, and the shaft 138 is driven by a chain 144 entrained over the sprockets 146 and 148 fixed to the shafts 100 and 138, respectively. The shaft 140 is, in turn, driven from the shaft 138 by meshing spur gears 150 and 152 on the shafts 138 and 140, respectively. It will be noted at this point that an eccentric 154 is fixed to the shaft 140, which, as will be seen shortly, serves to actuate the hand-held cutting assembly 64. The shaft 142 is also driven from the shaft 138 by means of a chain 156 entrained over sprockets 158 and 160 fixed on the shafts 138 and 142.

It will be appreciated that by virtue of the positive gear and chain drives provided, the travel speeds of the chains 22, 24, 38, 52, 56 and the rotary speeds of the shafts 140 and 142 will be directly proportional to the speed of rotation of the main shaft 84. The importance of this relation will be subsequently significant.

Before leaving Figure 13, it will also be seen that the circular saws 60 are mounted on a longitudinally extending shaft 162 that is rotatably mounted on the frame 12. The shaft 162 is driven by a prime mover 164 with a belt drive 166 entrained over pulleys 168 and 170 fixedly secured to the outlet shaft of the prime mover 164 and the shaft 162, respectively.

Proceeding to a detailed description of the machine 10, attention is first directed to Figures 1 and 3, wherein it will be seen that the 70 drilling machine 14 comprises a head 172 guided for sliding movement transversely of the longitudinal dimension of the frame 12 by pairs of guide rails 174 suitably secured to the frame 12, as clearly shown in the drawings.

Three aligned pairs of bearings 176 are mounted on the head 172 and have three parallel spindles 178 rotatably journaled therethrough. The opposite ends of each of the spindles 178 have drill bits 180 suitably secured thereto, it being noted that the bits 180 adjacent one end of the head 172 have a right-hand twist while the others have a left-hand twist. The head 172 carries a mounting bracket 182 which in turn supports an electric motor 184, and the armature shaft 186 of the motor is provided with a triple grooved pulley 188 that drives the spindles 178 by means of three drive belts 190 entrained over the pulley 188 and the sprockets 192 suitably mounted and secured on the spindles 178.

The head 172 is reciprocated by means of the eccentric collar 194 on the eccentric 92 and an arm 196 on the collar 194 pivoted at 198 to a depending bracket 200 carried by the head 172. As clearly shown in Figure 3, each full revolution of the shaft 84 will reciprocate the head 172 to cause the drill bits 180 to sequentially drill the lowermost blocks 16 in the hoppers 18 and 20.

It is contemplated that the drilling assembly 14 may utilize drill bits all having the same direction of twist, if desired, inasmuch as this may be accomplished by merely utilizing an electric motor 184 that is reversible, and incorporating electric switch means, not shown, for controlling the direction of rotation of the motor that would be, in turn, actuated by movement of the head 172 to cause the motor to turn in one direction when the head 172 completes its movement in one direction, and to cause the motor to rotate in the opposite direction when the head 172 completes its movement in the opposite direction.

It is also considered feasible that the drilling assembly 14 may be fixedly secured to the frame 12, and suitable means operated by the shaft 84, such as the carriage moving means to be presently described that is used in connection with the cutter assembly 64, be provided for causing the necessary relative movement of the blocks relative to the drilling assembly 14 for the drilling of the blocks 16. Such an alternative construction has not been illustrated herein for the reason that the illustrated form of the invention is thought to be considerably more preferable.

Throughout the hereinbefore described movements of the blocks 16 as urged by the chains 22, 24, 38, 52 and 56, the blocks 16 are slidingly supported on the horizontal top 26 of the machine. The upper flight of each of the chains 22, 24, 38, 52 and 56 is disposed in a suitable slot in the top 26. Since each of the chains is provided with identical means for engaging the blocks 16, a detailed description of only one such means is thought to be sufficient for all the chains. As shown in connection with conveyor chains 22 in Figure 11, it will be seen that an upstanding lug 202 is secured to the chain that extends upwardly above the upper surface of the top 26 to engage a block 16 supported thereon in the manner illustrated.

As best shown in Figures 1, 3, and 4, the chutes or hoppers 18 and 20 are of identical construction and in the preferred construction shown are formed of angle iron members 204 arranged as shown and suitably fixed to the top 26. It will be seen that the members 204 of each of the hoppers are sufficiently spaced to permit the bits 180 to enter the lowermost blocks 16 therein. In addition, the hoppers 18 and 20 directly overlie the chains 22 and 24, respectively, with the members 204 of each hopper being spaced a sufficient distance apart on opposite sides of the respective

chains to permit the lugs 202 thereon to travel through the lower portion of the hopper to engage the lowermost block therein, it being noted that the members 204 are cut out, as at 206, to permit the lowermost block to move from the hopper 5 upon engagement of a lug 202 therewith. It will be noted that interference between the operation of the arm 196 with the chain 24 during reciprocation of the drilling assembly 14 is avoided by entraining the lower flight of the chain 24 under 10 the sprocket 128 (see Figure 3).

It will be apparent, as thus far described, that the frequency of reciprocation of the drilling assembly 14 varies in direct ratio to the speed of advance of the chains 22 and 24. Upon this 15 basis, the lugs 202 are spaced on the chains 22 and 24 in staggered relation to each other, so that a lug 202 on the chain 22 will remove a block 16 from the hopper 18 while the lowermost block 16 in the hopper 20 is being drilled, and vice versa. 20

The joiners 30 and 32 are for the purpose of conditioning the adjacent sides of the blocks for the subsequent pinning operation, and are arranged between the travel paths of the chains 22 and 24 for planing the blocks travelling thereon 25 respectively.

As best shown in Figures 1, 4, and 15, the joiner 30 comprises a block guide 208 in which a cutter head or rotary planer 210 is rotatably journaled for rotation in a suitable recess 212 therein. The shaft 214 of the planer 10 is driven by means of an electric motor 216 with a belt 218 entrained over pulleys 220 and 222 fixed on the shaft 214 and the armature shaft of the motor 216, respectively. The block guide 208 and the motor 216 are mounted for vertical adjustment, respectively on vertical frame members 224 and 226 by fasteners 228 and 230 that are received in vertical adjustment slots, not shown, in the members 224 and 226, the arrangement being such that the 30 entire vertical height of the planer 210 may be utilized before sharpening of the same is necessary.

As best shown in Figures 1, 16 and 18, the joiner 32 comprises a block guide 232, which, like the 45 guide 208, has a rotary planer 234 rotatably mounted in a suitable recess 236 therein. The shaft 238 of the planer 234 is driven from an electric motor 240 through a drive belt 242 entrained over pulleys 244 and 246 fixed on the 50 shaft 238 and the armature shaft of the electric motor 240, respectively. Vertical upright supports 248 are fixedly secured to the frame 12, such supports having vertical adjustment slots 250 therein. The motor 240 is secured to a plate 252 by fasteners 254, and the plate is vertically adjustable with respect to the supports 248 by means of bolts 256 extending through suitable apertures in the plate 252, the slots 250, and 55 threaded into the guide 232, whereby the joiner 32 may be adjusted vertically as a unit to utilize the entire length of the planer 234 before resharpening the same.

Means is provided for yieldingly urging the blocks 16 into engagement with the guides 208 and 232, with only the means used in connection with the guide 208 shown, inasmuch as the construction employed in each case is identical. As shown in Figure 1, such means used in connection with the guide 208 comprises arms 258 pivoted to 70 vertical pins 260 carried by the frame 12, such arms 258 being yieldingly urged toward the guide 208 by arms 262 secured to the arms 258 and connected to tension springs 264 suitably anchored to the frame 12, it being noted that move-

ment of the arms 258 towards the guide 208 is limited by engagement of the arms 262 with stop pins 266. As readily apparent, the arms 258 serve to guide the blocks 16 and to yieldingly urge the same into engagement with the planer.

The alignment mechanism 34 is best shown in Figures 1, 4, and 9, wherein there is shown a bell-crank including arms 268 and 270 pivoted to a frame extension 272 at 274. The outer extremity of the arm 258 is pivoted to an arm 276 carried by a collar 278 on the eccentric 94 in an adjustable manner by a pivot bolt 280 extending through a selected one of the apertures 282 provided in the arm 276. The outer extremity of the arm 270 is similarly pivoted at 284 to a further arm 286. The arm 286 projects downwardly towards the top 26 and has a bar 288 secured transversely to its under side adjacent its lower end, which bar 288 is adapted to slide on the top 26 during oscillation of the arm 270, as caused by the rotation of the shaft 84.

While the bar 288 slides on the surface of the top 26 during movement from the full-line position of the same to the dotted line position thereof, as shown in Figure 4, means is provided to elevate the bar 288 during the latter portion of its return movement to the full-line position from the dotted-line position. Such means comprises a pair of ramps 290 pivoted, as at 292, to the in-turned portions of a pair of brackets 294 carried by the frame 12 above the top 26. As an inspection of the drawings will reveal, the bar 288 slides under the ramp 290 during movements toward the dotted line position, but on return movement towards the full-line position, the outer end portions of the bar 288 ride up on the ramp 290 to drop therebehind on passing the pivot 292.

It will thus be appreciated that as previously described, the aligning mechanism 34, through the action of the bar 288, moves blocks 16 received from the conveyor chain 24 to the conveyor chain 38. Inasmuch as a single block in the hopper 20 is drilled by the assembly 14 and a single block is moved by the mechanism 34 during the full revolution of the shaft 84, it is but a simple matter to synchronize the operation of the components. This may be easily accomplished in several ways, such as by properly setting the angular relation of the eccentrics 92 and 94, spacing the mechanism 34 from the assembly 14, or by selecting a suitable speed ratio for the conveyor chains 22 and 24 to the shaft 84 (with appropriate spacing of the lugs 202). However, with the provision of the ramps 290, the operative stroke of the bar 288 may lag considerably behind the delivery of a block 16 to the mechanism 34, as will be evident.

The lugs 202 on the conveyor chain 38 are so spaced and the over-all lengths of the conveyor chains 22 and 38 so related that the lugs 202 on the upper flights of these chains travel side by side. It will thus be seen that if the bar 288 moves a block 16 into position over the chain 38 before the block travelling on the chain 22 has arrived alongside thereof, the block on the chain 38 will 60 remain stationary until engaged by a lug 202 on the chain 38, so that the blocks will be moved toward the pinning station 50 only when they are in side-by-side relation.

In order to assist the guiding of a block on the chain 22 into the pinning station 50, an adjustable side guide rail 296 (see Figure 1) is provided. Adjustment of the rail 296 towards and away from the chain 22 is afforded by the mounting straps 298 of the rail 296 having slots 300

therein, with fasteners 302 extending through the slots 300 to secure the rail to the frame 12.

The construction of the pinning station 50 includes means for holding the blocks 16 temporarily against the movement longitudinally of the frame 12, this construction being best shown in Figure 7. As the blocks 16 approach the end of movement afforded the same by the chains 22 and 38, the blocks 16 engage spring-biased fingers 304 pivotally mounted on a pivot shaft 305. The fingers 304 are biased by springs 308 from the dotted line position thereof shown in Figure 7 towards the full-line position, such tension springs 308 being suitably secured to the fingers 304 and anchored to brackets 310 carried by a rigid frame member 312, with the member 312 serving as a stop, as clearly shown in the drawings.

Movement of the blocks 16 by the chains 22 and 38 moves the fingers 304 towards the dotted-line position thereof and serves to position the forward ends of the blocks 16 under hold-down straps 314 carried by a further rigid frame member 316, which, like member 312, is suitably secured to the frame 12. Latches 318 are pivoted to brackets 320 carried by a transverse element 322 of the frame 12 disposed above the top 26, as at 324. As will be evident, the blocks 16 are free to pass to the right under the latches 318, as viewed at 27. However, once the rear ends of the blocks 16 have cleared the dogs 326 on the latches 318, reverse movement of the blocks is prevented thereby.

The arrangement of sprockets 116 and 120 for the chains 22 and 38, respectively, with respect to the fingers 304 and the latches 318 is such that, prior to the disengagement of the lugs 202 on such chains with the blocks, the rear ends of the blocks will have moved past the dogs 326 and the fingers are engaged and moved by the blocks so that, upon disengagement of the lugs 202 with the blocks 16, the same are held against longitudinal movement relative to the frame 12 and in a predetermined relation to each other, inasmuch as a spring finger 304 and a latch 318 are provided for each pair of blocks. As clearly shown in Figure 7, the chains 52 travel under the blocks 16, when the latter are so positioned at the pinning station 50, so that when the side-by-side arranged lugs 202 on the chains 52 pass through the pinning station 50, the chains 52 move the blocks 16 from the pinning station 50, the fingers 304 yielding sufficiently to permit this movement. It will be understood, however, that sufficient time will elapse from the time the blocks are disengaged by the lugs 202 on the chains 22 and 38 before the blocks are engaged by lugs 202 on the chains 52 that the blocks will have been pinned together in the manner now to be explained.

Means 328 is provided for pushing the blocks 16 together after the same are engaged by the latches 318 and the fingers 304 and before the lugs 202 on the chains 52 engage the same. As best shown in Figures 2, 5 and 7, such means 328 comprises a sectional pusher rod 330 with a pusher plate 332 attached thereto and a pusher rod 334 with a pusher plate 336 attached thereto, such plates 332 and 336 being in opposed relation. The pusher rods 330 and 334 are mounted for longitudinal sliding movement in aligned bearing sleeves 338 and 340, respectively, mounted on opposite sides of the frame 12.

The ends of the rods 330 and 334 adjacent the shaft 84 are provided with rigid depending arms 342 and 344, respectively, and these arms have pivotal connection to arms 346 and 348 carried

by collars 350 and 352 rotatably secured on the eccentrics 96 and 98, respectively, it being noted that the eccentrics 96 and 98 have opposite dwells, whereby rotation of the main shaft 84 causes the plates 332 and 336 to reciprocate in opposite directions as indicated by the arrows 354 and 356. As clearly shown in the drawings, the plates 332 and 336 are so arranged with respect to the top 26 that the blocks 16 will be between the plates 332 and 336 and have the opposite sides thereof engaged by the plates.

As mentioned above, the pusher rod 330 is sectional, the same being formed of sections 358 and 360. The latter-mentioned section 360 is provided at one end with an enlarged collar 362 which slidably and guidingly receives the adjacent end portion of the section 358. Sections 358 and 360 are resiliently biased apart by a coiled compression spring 364 embracing the section 358 and seated between the collar 362 and a collar 366 fixed on the section 358, the arrangement being such that the spring 364 will yield and permit telescoping of the pusher rod 330 upon the plates 332 and 336 meeting resistance exceeding a predetermined amount in movements towards each other, such as would occur if dowel pins 70 were placed between the blocks 16 which were not in alignment with the openings 368 in the blocks 16. It should be noted at this point that if such a malfunction in the machine 10 should occur, for any reason, the blocks 16, although not joined together, would be removed from the pinning station 50 by the chains 52, so that a stoppage of the machine will not occur for this reason.

Means synchronized with the operation of the pusher rods 330 and 334 is provided for insuring the proper spacing of the blocks 16 before the plates 332 and 336 move towards each other, so that dowel pins 70 may be received therebetween.

Such means includes a pair of spacer plates (see Figures 2, 5 and 7) 370 and 372 mounted for substantially vertical movement at the pinning station 50, the plate 372 having a finger 374 fixed thereto that overlies the plate 370, so that the spacer plate 372 will rise and fall with the spacer plate 370, as will be evident. The vertical movements of the plate 372 is guided by means of an arm 376 secured thereto and pivoted to a horizontal pivot pin 378 suitably mounted on the sleeves 338 and 340. In a substantially analogous manner, the spacer plate 370 is supported and guided in its vertical movement by an arm 380 attached thereto and pivoted to the frame 12 for vertical swinging movement, as at 382. The arm 380 is provided with an upstanding bracket 384 that has a vertical adjustment slot 386 therein (see Figures 5, 6 and 17). A pin 388 extends horizontally through the slot 386 to overlie the section 360 of the pusher rod 330, the pin 388 being retained in adjusted vertical position in the slot 386 by adjustment nuts 390 threaded on the pin 388 and engaging the opposite sides of the bracket 384. The pin 388 rests on the top of the section 360 and is engaged by a cam 392 on the top of the section 368 to raise the arm 380, and, consequently, the spacer plates 370 and 372, during a predetermined portion of the movement of the pusher plate 332 toward the pusher plate 336, and to permit the spacer plates 370 and 372 to descend by their own weight upon reverse movement of the pusher plate 332, as will be evident upon a perusal of the drawings. The arrangement of the pin 388 with respect to the cam 392 is such that the spacer plates 370 and 372 will be in the lowered position to be disposed between blocks 16 entering or in

11

the pinning station 50 while the pusher plates 332 and 336 are spaced apart a distance exceeding the combined width of the two blocks 16 and either one of the spacer plates 370 or 372. It will, of course, be understood that the vertical adjustment afforded the pin 388 by the slot 386 permits the spacer plates 370 and 372 to be adjusted to correspond with the thickness of the blocks 16 to clear the latter upon being raised, and that the width of the spacer plates 370 and 372 slightly exceeds the length of the dowel pins 70, so that the latter may be received between the blocks 16 prior to the movement of the blocks 16 together by the action of the pusher plates 332 and 336.

Means 394 is provided for delivering dowel pins 15 70 to a position adjacent the pinning station 50 and for coating the dowel pins 70 with a suitable binding agent or glue. This construction is best shown in Figures 2, 5 and 7, and includes a dowel pin conveying chain 396 entrained over a sprocket 398 fixed on the shaft 142; a sprocket 400 fixed on a shaft 402 disposed between the shafts 106 and 108 and in the same horizontal plane as the shaft 142 (see Figure 13); and a sprocket 404 fixed on a shaft 406 disposed between and below the shafts 25 142 and 402. The chain 396 is provided with spaced sets of dowel pin supporting fingers 408. The fingers 403 are formed on spaced pairs of links 410 that form the chain 396, and the fingers 308 are arranged to extend upwardly from the 30 upper flight of the chain 396. The fingers 408 on each pair of chain links 410 are, of course, transversely spaced with respect to the longitudinal dimension of the chain 396, and have aligned recesses 412 formed in their upper ends, as viewed 35 on the upper flight of the chain 396, in which on the upper flight of the chain 396, in which dowel pins 70 are received, as clearly illustrated in the drawings.

The chain 396 is driven by the shaft 142 in the direction of the arrow 414, so that dowel pins 70 40 with slightly tapering opposite ends may be manually placed on the fingers 408 on the section of chain 396 passing between the pinning station 50 and the sprocket 398, so that spaced sets of pins 70 will travel along with the chain 396 over 45 the sprockets 398, 404 and 400 in the order listed to a position immediately below the pinning station 50, the pins 70 in each set corresponding in number and spacing to the openings 368 in the blocks 16 to be pinned thereby. The pins 70 are 50 prevented from falling from the lower flight of the chain 396 by means of spaced guides 416, L-shaped in cross-section (see Figure 5), extending along the lower flight of the chain 396 between the sprockets 398 and 404 and between the latter 55 sprocket and sprocket 400 to engage the oppositely extending ends of the pins 70 to retain the same in the recesses 412 formed in the fingers 408. A further guide strip 418 is provided to retain the chain 396 between the guides 416 extending between the sprockets 398 and 404, the guides 416 60 and the guide strip 418 being suitably secured to the frame 12 by means not shown.

As clearly shown in Figure 7, a glue pot 420 is provided which is suitably secured to the frame 65 12 and is arranged so that the dowel pins 70 passing around the sprocket 404 will be immersed therein, the lower end portion 422 of the guide strip 418 being arcuately shaped to partially surround the sprocket 404 to prevent glue from being 70 thrown by the sprocket 404 during the rotation thereof. It will thus be seen that the dowel pins 70 are delivered to a position immediately below the pinning station 50 with a coat of glue applied thereto.

12

Means, best shown in Figures 5, 7 and 12, is provided to raise or lift the sets of dowel pins 70 from the chain 396 as they pass below the pinning station 50, and to position the sets of pins 70 between the blocks 16 that are spaced by the spacers 370 and 372 before the pusher plates 332 and 336 urge the blocks 16 together. For this purpose, an elongated, U-shaped pin lifter 424 is provided which has aligned pairs of notches 426 in the upper edges of the transversely spaced legs or walls 428 thereof. The pairs of notches 426 correspond in number and spacing to the pairs of fingers 408 in each set, the arrangement being such that upon upward movement of the lifter 424 the walls 428 move upwardly from opposite sides of the chain 396 to engage the pins 70 adjacent the extremities of the latter to raise the pins 70 from the fingers 408 with the pins 70 being seated in the notches 426. The lifter 424 is mounted on the top of a guide column 430, the lower end of which is formed in a post 432 slidably received in a suitable aperture, not shown, in a guide bracket 434 for vertical movement.

Obviously, the action of the pin lifter 424 must be properly timed with the movement of the chains 396 and with respect to the action occurring at the pinning station 50. Inasmuch as the arrival of pins 70 below the pinning station 50 may be properly timed with respect to the action of the pinning station 50 by the length of the chain 396 and the spacing of the sets of fingers 408 thereon, by virtue of the correlation between the speeds of the shafts 84 and 142, it is only necessary to properly regulate the vertical reciprocation of the pin lifter 424 to the rotation of the shaft 84. In the present form of the invention, the necessary correlation between the rotation of the main or master shaft 84 and the action of the pin lifter 424 is achieved by the construction best shown in Figures 5 and 12, wherein it will be seen that a rod 436 is fixed at 438 to the arm 444, and is guided for reciprocatory movement parallel to the pusher rod 334 by a tubular guide 446 to an element of the frame 12. A pin lifting or elevating arm 442 is pivoted at 444 to the column 430, and at 446 is pivoted to the frame 12 for vertical movement.

Cam means is provided to swing the arm 442 upwardly during only a portion of the movement of the pusher plate 326 toward the plate 332 so as to raise the pins 70 carried by the pin lifter 424 into position between the blocks 16, and to hold the pin lifter 424 so elevated until the opposite ends of the pins 70 have commenced to be received in the dowel pin receiving openings 368 in the blocks 16, after which the arm 442 and, consequently, the lifter 424 are quickly lowered to permit the blocks 16 to be pushed together. Such cam means comprise an intermediate portion of the arm 442 being formed as an inverted U-shaped portion 448 adjacent a cam 450 fixed to the rod 436. An arm 452 is pivoted, as at 454, to the portion 448 for horizontal swinging movement and is arranged to cooperate with the cam 450 in raising the arm 442. The arm 452 is normally retained in the full-line position shown in Figure 12 by means of a tension spring 456 connecting the end of the arm 452 opposite the cam 450 from the pivot 454 to an ear 458 carried by the portion 448; such spring 456 serving to bias the arm 452 against an adjustable stop 460 threaded through the ear 458. As will be evident, upon an inspection of the drawings, the arrangement is such that movement of the rod 436 to the right, as viewed in Figure 5, will

13

cam the arms 452 and 442 upwardly until the arm 452 clears the left end of the cam 450, after which the arms 452 and 442 drop by gravity. Upon return or reverse movement of rod 436 to the left, the vertical face of the cam 450 engages the arm 452 to swing the latter about the pivot 454, as indicated in dotted outline in Figure 12, until sufficient clearance is afforded for the arm 452 to swing back to its full-line position under the action of the spring 456, so that reverse movement of the rod 436 does not cause the arms 452 and 442 to rise. It will therefore be apparent that it is only a simple matter in properly positioning and shaping the cam 450 to attain the desired movement of the pin lifter 424, which will, of course, be synchronized with the action that takes place at the pinning station 50, and also with the movements of the chain 396.

Figure 6 clearly illustrates the position assumed by the structure at the pinning station 50 and the dowel pin lifting mechanism after the blocks 16 have been pinned together, it being noted that the spacer plate 472 has been raised and the dowel pin lifter 424 has been lowered.

As previously described, the chains 52 move the blocks 16 after they have been pinned together to form a panel from the pinning station 50, and the chains 56 receive the panels from the chains 52 and move the same between the rotary saws 60. The structure 62 for holding the panels down during their movements between the saws 60 includes a weighted shoe 464 suspended by flexible straps 466 secured to a bar 468 carried by supporting portions 470 of the frame 12. The under side of the shoe 464 is beveled at 472 to facilitate the movement of a pair of pinned blocks 16 or a panel therebelow.

Attention is now directed to Figures 2, 6, 8, and 10 for an understanding of the hand-hold cutting assembly 64. A carriage or carrier 474 is guided for sliding movement transverse to the travel of the chains 56 and parallel to the longitudinal dimension of the frame 12 by parallel spaced guides 476, the upper surfaces of which are coplanar with the upper surface of the top 26. As clearly shown, the opposite edges of the carrier 474 are received in guide grooves 478 formed in the adjacent sides of the guides 476. In a manner analogous to the case of the pinning station 50, the blocks are pushed onto the guides 476 by the lugs 202 on the chains 56 against spring biased fingers 480 pivoted for vertical swinging movement, as at 482, and biased to the full-line position shown in Figure 6 by tension springs 484. The fingers 480 urge rearward or reverse movement of the blocks 16 against the urging of the chains 56, so that when the lugs 202 on the chains 56 clear the trailing edges of the blocks 16, the blocks 16 are moved rearwardly to engage the latches 486 pivoted at 488 for vertical swinging movement. A pair of frame members 490 and 492 transversely bridge the path of the blocks 16 as they move into and through the cutter assembly 64, and a pair of hold-down strips 494 are secured to the members 490 and 492 to prevent vertical movement of the blocks 16, it being noted that the latches 486 are supported on the member 490.

The carriage 474 is provided with an upstanding flange 496 between the guides 476 that projects upwardly above the surface of the guides 476. As will be seen presently, the carriage 474 is disposed in such a position that the flange 496 will not interfere with the movement of the blocks 16 onto the guides 476 by the chains 56, the pur-

5

pose of the flange 496 being to subsequently engage the side of the pinned block 16 and move the latter into engagement with the cutter 66 during reciprocation of the carriage 474.

The carriage 474 is reciprocated by means of a sectional pusher rod 498 that is pivoted to a depending bracket 500, as at 502, carried by the carriage 472 between the guides 476, such rod 498 being also secured to a collar 504 rotatable on the eccentric 154. The sectional pusher rod 498 is formed of a section 506 that telescopes into a tubular section 508, the rod 498 being biased to its extended position by means of a coiled compression spring 510 embracing the sections 506 and seated between collars 512 and 514, fixed on the sections 506 and 508, respectively, so as to afford a pressure relief.

Since the reciprocation of the carriage 474 is caused by rotation of the shaft 140, it will be seen that the same operates in timed relation to the shaft 64, and, consequently, the other parts of the machine 10. Accordingly, the movements of the carrier 474 are timed with the reception of blocks 16 on the guides 476 and the seating of the blocks 16 against the latches 486, the eccentric 154 being so positioned on the shaft 140 that movement of the carriage 474 towards the cutters 66 occurs during the time that the blocks 16 are engaged by the latches 486. It will, of course, be understood that the eccentric 154 is of sufficient throw to permit the proper seating of the blocks 16 before the latter are engaged by the flange 496 to be moved towards the cutters 66.

While the blocks 16 are being moved towards the cutters 66, they engage spring-pressed rods 516 that hold the blocks 16 in engagement with the flange 496, such rods 516 serving to move the blocks 16 back to the position occupied thereby before they were engaged by the flange 496 upon retreating movement of the carriage 474. As clearly shown in Figure 10, each of the rods 516 is mounted for longitudinal reciprocation through suitable guide apertures and guide members 518 and 520 suitably mounted on the frame 12. Each of the rods 516 is yieldingly urged towards the shaft 140 by a tension spring 522 connecting the rod to the guide member 518. In addition, each of the rods 516 is provided with an enlarged portion 524 that constitutes a stop that strikes the member 520 to limit movement of the rod 516.

It will thus be seen that the carriage 474 moves the blocks 16 into the cutter 66 driven by the motor 526 mounted, as at 528, to the frame 12, and that the rods 516, disposed on opposite sides of the cutter 66, urge the blocks 16 away from the cutter after they have been operated on thereby.

After a pair of blocks 16 have been cut to produce a hand-hold opening 72 and have been returned to the position occupied thereby before being moved by the carriage 474, the pair of blocks 16 are urged from the cutter assembly 64 by the movement of a subsequent pair of blocks 16 thereonto, the blocks 16 having been pinned and cut to form the completed product 68, shown in Figure 14, being discharged from the machine 10 down the inclined apron 532, it being noted that the fingers 480 swing to the dotted line position shown in Figure 6 to permit the product 68 to leave the machine.

Without further elaboration, it is believed that the operation and the benefits attained by this invention will be readily apparent to those skilled in the art. While certain portions of the ma-

14

pose of the flange 496 being to subsequently engage the side of the pinned block 16 and move the latter into engagement with the cutter 66 during reciprocation of the carriage 474.

The carriage 474 is reciprocated by means of a sectional pusher rod 498 that is pivoted to a depending bracket 500, as at 502, carried by the carriage 472 between the guides 476, such rod 498 being also secured to a collar 504 rotatable on the eccentric 154. The sectional pusher rod 498 is formed of a section 506 that telescopes into a tubular section 508, the rod 498 being biased to its extended position by means of a coiled compression spring 510 embracing the sections 506 and seated between collars 512 and 514, fixed on the sections 506 and 508, respectively, so as to afford a pressure relief.

Since the reciprocation of the carriage 474 is caused by rotation of the shaft 140, it will be seen that the same operates in timed relation to the shaft 64, and, consequently, the other parts of the machine 10. Accordingly, the movements of the carrier 474 are timed with the reception of blocks 16 on the guides 476 and the seating of the blocks 16 against the latches 486, the eccentric 154 being so positioned on the shaft 140 that movement of the carriage 474 towards the cutters 66 occurs during the time that the blocks 16 are engaged by the latches 486. It will, of course, be understood that the eccentric 154 is of sufficient throw to permit the proper seating of the blocks 16 before the latter are engaged by the flange 496 to be moved towards the cutters 66.

While the blocks 16 are being moved towards the cutters 66, they engage spring-pressed rods 516 that hold the blocks 16 in engagement with the flange 496, such rods 516 serving to move the blocks 16 back to the position occupied thereby before they were engaged by the flange 496 upon retreating movement of the carriage 474. As clearly shown in Figure 10, each of the rods 516 is mounted for longitudinal reciprocation through suitable guide apertures and guide members 518 and 520 suitably mounted on the frame 12. Each of the rods 516 is yieldingly urged towards the shaft 140 by a tension spring 522 connecting the rod to the guide member 518. In addition, each of the rods 516 is provided with an enlarged portion 524 that constitutes a stop that strikes the member 520 to limit movement of the rod 516.

It will thus be seen that the carriage 474 moves the blocks 16 into the cutter 66 driven by the motor 526 mounted, as at 528, to the frame 12, and that the rods 516, disposed on opposite sides of the cutter 66, urge the blocks 16 away from the cutter after they have been operated on thereby.

After a pair of blocks 16 have been cut to produce a hand-hold opening 72 and have been returned to the position occupied thereby before being moved by the carriage 474, the pair of blocks 16 are urged from the cutter assembly 64 by the movement of a subsequent pair of blocks 16 thereonto, the blocks 16 having been pinned and cut to form the completed product 68, shown in Figure 14, being discharged from the machine 10 down the inclined apron 532, it being noted that the fingers 480 swing to the dotted line position shown in Figure 6 to permit the product 68 to leave the machine.

Without further elaboration, it is believed that the operation and the benefits attained by this invention will be readily apparent to those skilled in the art. While certain portions of the ma-

chine have been described in considerable detail, the scope of the invention is not to be deemed limited by such detailed description. On the other hand, other less novel features or structures readily perceived upon inspection of the drawings have either been described briefly or omitted entirely in the description, such as various guide walls along the travel path of the blocks 18, and so forth, in order not to unduly extend this specification, it being thought that such additional matter would tend to obscure rather than point up the paramount features of merit of this invention.

It should be further stated that numerous changes in the specific construction of the invention are contemplated, such as the substitution of various equivalent coordinating mechanisms for the eccentric and cam means herein disclosed and described, and it is also thought that further labor economy may be effected in the use of the machine by the provision of an automatic means, not shown, for feeding dowel pins 10 to the chain 39.

Since, from the foregoing, the construction and advantage of this machine are readily apparent, further description is believed to be unnecessary.

However, since numerous modifications and equivalents will readily occur to those skilled in the art after a consideration of the foregoing specification and accompanying drawings, it is not intended to limit the invention to the exact embodiment shown and described, but all suitable modifications and equivalents may be resorted to which fall within the scope of the appended claims.

Having described the invention, what is claimed as new is:

1. In a dowel pinning machine, a support platform, a pair of spaced vertical block feeding chutes on the platform, a pair of spaced parallel endless conveyor chains mounted on the platform and extending below the chutes for moving a pair of blocks along parallel paths on the platform, spaced and staggered block engaging means on the pair of chains for alternately engaging blocks at the bottom of the chutes and removing the blocks therefrom, drilling means disposed between the chutes and movably mounted for movement between the chutes for selectively drilling dowel pin receiving openings in the adjacent sides of blocks in the chutes, means for reciprocating the drilling means in timed relation to the movement of the block engaging means, a further endless conveyor chain arranged parallel to and spaced from one of the pair of conveyor chains, spaced block engaging means on the further conveyor disposed in transverse alignment with respect to the spaced block engaging means on the other of said pair of conveyor chains whereby the openings in blocks engaged thereby are in alignment, and means operating in timed relation to the movements of the block engaging means on said one conveyor chain to move a block engaged thereby from such engagement and into the travel path of the block engaging means of the further conveyor, whereby the individual blocks of a series of pairs of blocks are sequentially drilled and the blocks of each pair of blocks moved along parallel paths with the drilled openings therein in alignment.

2. In a dowel pinning machine, first, second and third parallel endless conveyor chains, block supporting means adjacent said chains, spaced means on each of the conveyor chains for engaging and moving a block supported by the sup-

porting means, said last means on the second chain being in transverse alignment with respect to the corresponding means on the third chain so that the dowel pin receiving openings in a pair of blocks engaged by such means on the second and third chains are in alignment, means disposed adjacent an end of said first chain for moving a block from engagement with the block engaging means on the first chain and into the travel path of the corresponding means on the third chain, whereby the dowel pin openings in a pair of blocks may be aligned, means disposed adjacent the ends of said second and third chains for periodically placing a dowel pin between blocks having aligned dowel pin receiving openings, and means adjacent said dowel pin placing means operating in timed relation to the last stated means for urging the blocks towards each other.

3. In a dowel pinning machine, first, second and third parallel endless conveyor chains, block supporting means adjacent said chains, spaced means on each of the conveyor chains for engaging and moving a block supported by the supporting means, said last means on the second chain being in transverse alignment with respect to the corresponding means on the third chain so that the dowel pin receiving openings in a pair of blocks engaged by such means on the second and third chains are in alignment, means disposed adjacent an end of said first chain for moving a block from engagement with the block engaging means on the first chain and into the travel path of the corresponding means on the third chain, whereby the dowel pin openings in a pair of blocks may be aligned, means disposed adjacent the ends of said second and third chains operating in timed relation to the movements of the second and third chains for urging the blocks together, said last means including a pair of relatively movable members along a line transverse to the travel path of the second and third chains, and means disposed between said movable members responsive to a predetermined relative movement of the members to move a dowel pin between the blocks.

4. In a dowel pinning machine, first, second and third parallel endless conveyor chains, block supporting means adjacent said chains, spaced means on each of the conveyor chains for engaging and moving a block supported by the supporting means, said last means on the second chain being in transverse alignment with respect to the corresponding means on the third chain so that the dowel pin receiving openings in a pair of blocks engaged by such means on the second and third chains are in alignment, means disposed adjacent an end of said first chain for moving a block from engagement with the block engaging means on the first chain and into the travel path of the corresponding means on the third chain whereby the dowel pin openings in a pair of blocks may be aligned, means disposed adjacent the ends of said second and third chains operating in timed relation the movements of the second and third chains for urging the blocks together, said last means including a pair of relatively movable members along a line transverse to the travel path of the second and third chains, a dowel pin support mounted between said movable members for movement transverse to the travel path of the second and third chains and also transverse to the line of relative movement of the members, and means for moving the dowel pin support in response to a predetermined rela-

tive movement of the members, means connecting said means for moving the dowel pin support and the members so that a dowel pin supported by the dowel pin support will be moved between a pair of blocks during the time interval between movements of the members to urge the blocks together.

5. In a dowel pinning machine, first, second and third parallel endless conveyor chains, block supporting means adjacent said chains, spaced means on each of the conveyor chains for engaging and moving a block supported by the supporting means, said last means on the second chain being in transverse alignment with respect to the corresponding means on the third chain so that the dowel pin receiving openings in a pair of blocks engaged by such means on the second and third chains are in alignment, means disposed adjacent an end of said first chain for moving a block from engagement with the block engaging means on the first chain and into the travel path of the corresponding means on the second chain, whereby the dowel pin openings in a pair of blocks may be aligned.

6. In a dowel pinning machine, a support platform, a first conveyor means disposed adjacent said platform for urging forward movement of a pair of transversely spaced blocks onto said platform, means carried by said platform adapted to yieldingly urge rearward movement of the blocks, said first conveyor means and the urging means being longitudinally spaced so that the first conveyor means will become disengaged from the blocks upon a predetermined yielding movement of the urging means, latch means carried by said platform for limiting rearward movement of the blocks on the platform, transversely spaced members adjacent opposite sides of the platform for receiving the blocks therebetween, means operable in timed relation to the first conveyor means for periodically causing relative opening and closing movement of the members to urge the blocks therebetween towards each other, a second conveyor means carried by said platform for moving dowel pins to a position adjacent the platform, and drive means operatively connected to the members for periodically moving a dowel pin from the second conveyor means to a position between the members so that upon closing movement of the members the pin will be forced into aligned openings in the adjacent sides of the blocks.

7. A dowel pinning machine comprising, a support platform, first and second spaced block feeding chutes, a pair of spaced parallel endless conveyor chains mounted on the platform for moving a pair of blocks forwardly along parallel paths on the platform, said chains having portions underlying said chutes, spaced and staggered block engaging means on the pair of chains for alternately engaging blocks in the chutes and removing the blocks therefrom, drilling means disposed between the chutes and movably mounted for movement between the chutes for selectively drilling dowel pin receiving openings in the adjacent sides of blocks in the chutes, means carried by said platform for reciprocating the drilling means in timed relation to the movement of the block engaging means, a further endless conveyor chain arranged parallel to and spaced from said first conveyor chain, spaced block engaging means on the further endless conveyor that are transversely aligned with respect to the spaced block engaging means on said second chain so that the openings in blocks en-

gaged thereby are in alignment, means disposed adjacent an end of said first chain operating in timed relation to the movements of the block engaging means on said one chain to move a block engaged thereby from such engagement into the travel path of the block engaging means on the further conveyor, means adjacent the ends of said second chain and said further conveyor for yieldingly urging rearward movement of the blocks, latch means disposed adjacent said urging means for limiting rearward movement of the blocks, said block engaging means on the further chain and on said second chain being longitudinally spaced with respect to the urging means that the block engaging means will disengage the blocks upon a predetermined yielding movement of the urging means, means including a pair of relatively movable members disposed adjacent said urging means for urging blocks engaged by the urging means together, and means connected to actuating means for the members for periodically placing a dowel pin between the blocks engaged by the urging means.

8. In a dowel pinning machine, an elongated supporting frame, a pair of spaced block feeding chutes carried by said frame, first and second conveyors carried by said frame and underlying said chutes, block engaging means on each of the first and second conveyors for moving a pair of blocks from the chutes along parallel paths, the last mentioned means on the first conveyor being staggered with respect to such means on the second conveyor so that the blocks of a pair of blocks will be sequentially moved from the chutes, means carried by said frame between said chutes for sequentially boring dowel pin receiving openings in adjacent sides of the pair of blocks prior to both the blocks being engaged by the block engaging means on the first and second conveyors, means carried by said frame for reciprocating the last mentioned means between the chutes in timed relation to the operation of the block engaging means on the first and second conveyors, a third conveyor mounted on said frame between said first and second conveyors, block engaging means on the third conveyor for moving one of the pair of blocks along a path parallel to the first mentioned paths, said block engaging means on both the second and third conveyors being transversely aligned with respect to each other so that the dowel pin receiving openings in the pair of blocks engaged thereby will be in alignment, means disposed adjacent an end of said first conveyor for moving a block from the block engaging means on the first conveyor to the block engaging means on the third conveyor, means carried by said frame adjacent the ends of said second and third conveyors for moving a dowel pin into a position between a pair of blocks and into and in alignment with the dowel pin receiving openings therein, and means carried by said frame adjacent said last mentioned means for urging the blocks together.

9. A dowel pinning machine comprising a supporting frame, a pair of block stackers, oppositely moving means for alternately drilling dowel pin receiving openings in the adjacent sides of two stacks of blocks retained in said block stackers carried between the block stackers, spaced means carried by said frame partially disposed below said block stackers for alternately moving drilled blocks from the two stacks to a pinning station disposed adjacent said block moving means and also for arranging a block moved from one stack with respect to a block moved from the other

19

stack in spaced relation with the openings therein aligned, means located between said spaced means and carried by said frame at said pinning station for positioning a dowel pin between blocks arranged by the last-mentioned means in alignment with the openings therein, and means carried by said frame at the pinning station for urging the blocks together.
